UNITED STATES PATENT OFFICE.

ISIDOR MENSCH, OF NEW YORK, N. Y., ASSIGNOR TO LEON MANN COMPANY, A CORPORATION OF NEW YORK.

SAFETY SECRET POCKET FOR GARMENTS.

No. 913,749.

Specification of Letters Patent.

Patented March 2, 1909.

Application filed September 7, 1907. Serial No. 391,768.

To all whom it may concern:

Be it known that I, ISIDOR MENSCH, a subject of the Emperor of Austria, and a resident of the borough of Brooklyn, in the county of 5 Kings, city and State of New York, have invented certain new and useful Improvements in Safety Secret Pockets for Garments, of which the following is a specification.

My invention relates to pockets for garments, and particularly to safety concealed or "secret" pockets adapted to be located on the outside of coats and other garments. Its 10 objects are, among others, to provide a pocket of this character of simple, strong and durable construction, which may be applied 15 to garments worn by members of both sexes and which will be effectively concealed.

The invention consists of the construction, combination and arrangement of parts here- 20 inafter described and claimed and illustrated in the accompanying drawings.

In the said drawings, Figure 1, is an outside view of a detachable portion of a garment provided with a pocket embodying the 25 invention. Fig. 2, is a vertical section of the same taken on the line 2—2 of Fig. 1.

A visible pocket K, is formed by the walls H and L and has its opening at N, immediately above the flap A, while the concealed 30 pocket J is formed by the walls G and H and has its top opening beneath the flap A and at the upper edge of the part D. The lower edges and sides of the walls G, H and L are stitched together and the upper portion of 35 each wall is secured to the cloth of which the garment is made. Thus the wall G is secured in the turned over portion E of the part D, the wall H is secured to the back of the turned down portion I of the flap A and 40 the wall L is stitched to the back of the extension F of the portion M, and preferably extends up a short distance over the back of the part M where it is also secured. The entrance to the pocket K is between the upper 45 ends of H and F, and the entrance to the pocket J is between the upper folded edge of E and I.

The flap A is of ordinary form and is secured at its lower point by means of the button-hole B and button C. It will be understood, however, that this flap may be of any 50 desired form, and that it may be constructed

so as not to have the appearance of a flap. This will be of particular advantage in ladies' garments. It will be observed that the portion of the garment beneath the flap 55 is composed of four thicknesses of the material of which the garment is made as well as the upper portions of the three pocket walls. This arrangement provides a body of considerable thickness into which the flap A 60 may be pressed as shown in the drawings, so that it will have the appearance of being a part of the material D and will not suggest the presence of a pocket beneath it. It also permits the folded over part E to be 65 pressed into the part I so that the opening of the secret pocket will not be visible if the flap A is raised.

This pocket is not only a secret pocket but a safety pocket. It will be observed that 70 the upper pocket K can be conveniently used for a handkerchief or to receive other articles frequently inserted and removed, while the pocket J, may be conveniently used as a receptacle for money, tickets, valuables or other 75 articles not frequently used, which it is desired to carefully preserve. Being in a separate pocket these articles will not be liable to be drawn out with the handkerchief or other articles of small value. The arrangement of 80 the two pockets and the flap is also important to the matter of safety as well as secrecy for the reason that it is impossible for a handkerchief for instance to be thrust into the secret pocket by mistake, or for valuables to 85 be placed in the non-secret pocket by mistake, unless the wearer is guilty of extreme carelessness.

What I claim is:—

The combination with the cloth forming 90 the body of the garment slitted, the upper part above the slit having an extension inside of the lower edge of the slit, a folded flap embracing the lower edge of the slit, one fold on the outside and the other on the inside there- 95 of, the inner fold resting against but free from said extension, leaving an opening between the said inner fold of the flap and the extension and one between the inner fold and the lower edge of the slit, a pocket wall se- 100 cured at its upper edge to the inside of the extension of the upper wall of the slit, another

5 pocket wall secured at its upper edge upon the inside of the inner fold of the flap, and a third wall secured at its upper edge to the lower edge of the slit, the three pocket walls having their side and bottom edges secured together, all substantially as described.

Witness my hand this 19th day of August,

1907, at the city of New York, in the county and State of New York.

ISIDOR MENSCH.
